[57] CLAIM

The ornamental design for an athletic glove, as shown
and described.

DESCRIPTION

FIG. 1 is a front elevational view of an athletic glove
showing my new design, wherein all broken lines in this
and all Figures represent stitching;

FIG. 2 is a rear elevational view thereof;

FIG. 3 is a left end elevational view thereof;

FIG. 4 is a right end elevational view thereof;

FIG. 5 is a bottom plan view thereof; and

FIG. 6 is a top plan view thereof.
